UNITED STATES PATENT OFFICE.

DAVID D. DICKSON, OF KANSAS CITY, MISSOURI.

BARBER'S CHAIR.

1,119,408.

Specification of Letters Patent.

Patented Dec. 1, 1914.

Application filed August 6, 1912. Serial No. 713,522.

To all whom it may concern:

Be it known that I, DAVID D. DICKSON, a citizen of the United States, residing at Kansas City, in the county of Jackson and State of Missouri, have invented certain new and useful Improvements in Barbers' Chairs; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to an operator's seat for barber chairs, and has for its principal object to provide a seat which may be attached to an ordinary barber's chair and is adapted for adjustment thereon so that it may be occupied by a barber or manicurist when a customer is seated in the main chair.

It is also an object of my invention to provide an auxiliary seat which may be folded when not in use so that it may hang beneath the main chair, but which may be extended and supported in a convenient position when it is to be occupied.

It is a further object of the invention to provide the auxiliary seat with a foot rack, which may be extended to a convenient position for supporting the foot of the customer while his shoe is being polished, and which may be folded toward the chair pedestal and carried wholly by the auxiliary chair support when not in use.

In accomplishing these objects, I have provided the improved details of structure hereinafter described and illustrated in the accompanying drawings, wherein:

Figure I is a perspective view of a barber chair of ordinary construction, and equipped with my auxiliary seat. Fig. II is a front elevation of the pedestal and side view of the seat, showing the latter in collapsed condition, in dotted lines. Fig. III is a detail view of the chair supporting ring.

Referring more in detail to the parts:— 1 designates a barber chair of ordinary construction, having a hydraulic pedestal 2 and plunger 3. Pivotaly mounted on the plunger 3, and supported thereon by a collar 4 which is fixed in an adjusted position on the pedestal by a set screw 5, is a collar 6, having laterally directed arms 7, the outer

ends of which are spaced to provide a channel 8 therebetween.

The collar is preferably formed in two pieces so that it may be applied to the plunger, the arm ends of the pieces being 60 connected by rivets or bolts 9 and the abutting ends by an overlapping strap 10, so that the diameter of the collar may be kept constant to obviate its working loose or binding against the plunger. The outer 65 ends of the arms 7 are brought together to form ears 11 which carry a pin 12, the ends of which project laterally and, in turn, carry brace bars 13, the latter being curved downwardly and inwardly toward the pedestal 2 and provided with end flanges 14 which bear against the pedestal and are adapted to travel thereover when the seat is moved around the chair.

Pivotaly mounted on the pin 12 which 75 carries the brace bars are straps 15 which carry a seat 16 and have a latch 17 pivotaly connected therewith and projected between the brace bars 13, the latch being curved so that when the seat is lowered it 80 may project up between the brace bars and between the spaced collar arms 7. The lower edge of the latch 17 has inner and outer notches 18 and 19 which are adapted to engage a pin 20 that projects between the 85 brace bars 13 to hold the seat extended or limit its inward movement when collapsed.

Fixed between the arms 7 and brace bars 13 is a standard 21 which is adapted to stiffen the collar arms and brace bars and is 90 provided with a laterally-turned lip 22 at its lower end. Pivotaly mounted on the lip 22 is a single lazy-tong 23, the outwardly progressive members of which overlap the inner members so that when the tong is 95 folded it will lie above the standard ear. Connected with the outer link of the lazy-tong is a stand 24, having a foot-rest 25, adjustably mounted thereon, and provided with rubber shoes 26 so that it will remain 100 in adjusted position on the floor. A box 27 is mounted on the outer link adjacent the standard and is adapted for carrying brushes and polish conveniently for the bootblack.

Presuming the parts to be constructed and assembled as described, when the seat is not in use it may be folded or collapsed, as is shown by dotted lines in Fig. II, the foot-rest being folded and supported snugly be- 110

neath the chair and out of contact with the floor. Should the barber or manicurist wish to use the chair, the seat may be lifted out by pivoting the arms 15 on the pin 12, the 5 latch dragging over the pin 20 until the notch 18 is over the pin when the chair would be released, and its weight will throw the latch into locking engagement with its pin. When the chair is extended in this manner, 10 it may be moved around the main chair to a desired position so that it can be used by the barber, or may be moved toward the front of the chair for use by the manicurist.

When the plunger is raised or lowered, in 15 the ordinary manner, the collar 4 supports the pivotally mounted collar so that the latter rises and falls with the plunger, thereby maintaining the auxiliary chair at the same relative elevation.

20 It is apparent that the foot-rest may be extended when needed, and may be moved either to the right or left of the foot-rest

on the main chair, and that it may be used to accomplish its function irrespective of the position of the auxiliary chair. 25

Having thus described my invention, what I claim as new therein and desire to secure by Letters-Patent, is:—

The combination with a chair comprising a pedestal and a plunger adapted for vertical adjustment in the pedestal, of a collar fixed on the plunger, a collar pivotally mounted on the plunger and supported by the fixed collar, an auxiliary seat carried by the loose collar, and a brace member frictionally engaging the pedestal and partially supporting the seat. 30

35 In testimony whereof I affix my signature in presence of two witnesses.

DAVID D. DICKSON.
